MYRON E. HASKELL, OF LOWELL, MASSACHUSETTS.

Letters Patent No. 89,043, dated April 20, 1869.

IMPROVEMENT IN SHUTTLE-BINDER FOR LOOMS.

The Schedule referred to in these Letters Patent and making part of the same.

To all whom it may concern:

Be it known that I, MYRON E. HASKELL, of Lowell, in the county of Middlesex, and State of Massachusetts, have invented new and useful Improvements in Shuttle-Binders for Looms; and I do hereby declare that the following is a full and exact description thereof, reference being had to the accompanying drawings, and to the letters of reference marked thereon.

The nature of my invention consists in providing for looms an improved shuttle-binder, its object being to secure the shuttle easily and safely in the box of the lathe, whilst in motion, when thrown from its opposite end, requiring much less power to operate the same, and providing a better security against damage and wear to the shuttle and picker-staff, and other parts of the machine.

To enable others skilled in the art to make and use my invention, I will proceed to describe its construction and operation.

Figure 1 represents a plan of one side of a loom, with my improved device attached.

Figure 2 represents a side elevation of the same.

Similar letters in the different figures indicate corresponding parts.

a represents the loom-side.

b b, the girts.

c, the lathe, which connects and swings on the shaft *d*, this shaft being secured to the bottom girt *e*.

Attached to the end of the shaft *d*, is a suitable device, which receives and is pivoted to one end of the picker-staff *e*, the other end of which passes through and operates in a slot made in the shuttle-box *f*.

Secured by a pivot to the box *f*, is the binder *g*, to one end of which a finger, *h*, is hinged, and the other end of this finger receives the stroke of the picker-staff *e*, and is retained in position by means of the spring *i*, the other end of the binder *g* being provided with a suitable spring, *j*, the object of this spring being to keep the binder in the required position, so that the shuttle, as shown in fig. 1, by dotted lines, may enter the box *f* freely, without coming in contact with and damaging the same.

k represents a handle, which is connected with the picker-staff *e*, by a cord, to facilitate and illustrate the operation of explaining my device.

The devices now in common use for receiving and securing the shuttle in the box, are supplied with binders, which project inwardly, leaving the space between the inside of the binder and the back board much less than the width of the shuttle, and are kept firmly in

this position, by a stiff spring, when the shuttle is not in the box.

The shuttle being necessarily of the heaviest kind of wood, its weight increased by being saturated with oil, and mounted with iron, makes it heavy, requiring great power to throw it back and forth, extra power being required with this common arrangement, in consequence of the spring before mentioned.

And further, at every throw of the shuttle on its entering the boxes, it meets the binder, by the stiffness of the spring and inertia of the same, receiving constantly damaging blows on the front part of the shuttle, at each end at the curves, so much so that in a very short time the shuttle becomes damaged in this locality, and unfit for use.

And again, by this extra force required, the picker-staves are as often and constantly receiving these damaging blows, and in a short time are rendered unfit for use, there being nothing behind or connected to them, to lessen and ease the blow.

Furthermore, great damage is done to the cop, or quill, of filling, at every other stroke, in consequence of the concussion the shuttle receives, in coming in contact with the binder and picker-staff.

These several serious difficulties are almost entirely remedied by my improved device, which operates as follows:

The shuttle, on leaving the box, is thrown through the warp into the opposite box, meeting with no obstruction from the binder *g*, but coming directly in contact with the picker-staff *e*, which receives the shuttle on its tip, thus throwing the finger *h* back, which, by aid of the spring *i*, eases and softens the blow of the shuttle against the picker-staff *e*, at the same time closing the binder *g* firmly and securely against the shuttle, as shown in fig. 1, thus stopping the same.

The shuttle, in being thrown back to the opposite box, receives aid in starting by the spring *i* contracting, which entirely relieves and disengages the binder *g* from the shuttle, the binder *g* being kept in position by aid of the spring *j*.

What I claim as my invention, and desire to secure by Letters Patent, is—

The finger *h*, and spring *i*, in combination with the binder *g*, substantially as and for the purposes herein described.

MYRON E. HASKELL.
